R. L. ESSON

POST FOR LOOSE LEAF BINDERS

Filed Aug. 28, 1920

Fig. 2.

UNITED STATES PATENT OFFICE.

ROBERT LYGERTWOOD ESSON, OF JOHANNESBURG, TRANSVAAL, SOUTH AFRICA.

POST FOR LOOSE-LEAF BINDERS.

Application filed August 28, 1920. Serial No. 406,732.

To all whom it may concern:

Be it known that I, ROBERT LYGERTWOOD ESSON, a subject of the King of Great Britain, and resident of Johannesburg, Transvaal Province, Union of South Africa, have invented certain new and useful Improvements in Posts for Loose-Leaf Binders, of which the following is a specification.

The invention relates to posts for loose leaf binders, loose leaf ledgers and the like. Extensible posts or pillars as now constructed for loose leaf binders, et cetera, are made of cylindrical shape and the posts are built up as required of the requisite number of sections or parts, screwed or otherwise connected together. On the other hand the adjustable thongs, straps, ribbons or bands provided in loose leaf ledgers, et cetera, to engage with the binding margin of the sheets are usually of substantially rectangular shape. To allow sheets used with such binders to be placed on the ordinary cylindrical posts, it has been the practice to provide in the binding margin of the sheets two or more key-hole slots or perforations to engage with the cylindrical posts, and with two or more T or similarly shaped slots for engaging with the adjustable thongs, et cetera, of loose leaf ledgers, et cetera.

Now the primary object of the present invention is to construct a sectional post in such a way that the sheets need only be constructed with the marginal slots or perforations necessary for engaging with the adjustable thongs, and the ordinary key-hole slots dispensed with. This allows the sheets to be removed from a thong, et cetera, ledger or binder and placed on the post binder, or vice versa, so that the sheets may be said to be interchangeable with only one form of marginal slots. It will be understood that the cost of providing one of the two sets of perforations or slots is saved and that, consequent upon the sheets being provided with only one set of slots, the sheets are stronger along the binding margin.

Certain features of this invention, in particular the means for constructing the sections, could be adopted in the construction of a sectional post of cylindrical, oval or other like shape.

The invention will be fully explained in connection with the accompanying drawings, wherein various forms of the invention are illustrated.

In the drawings,

Fig. 1 is a front elevation of a portion of a built up or extensible post comprising a lowermost section, an intermediate section and a top section.

Fig. 2 is a plan view of Fig. 1.

Fig. 3 is a sectional side elevation on line x-x, of Fig. 1.

Fig. 4 is a sectional front elevation similar to Fig. 1 of another form of the invention.

Fig. 5 is a plan of Fig. 4.

Fig. 6 is a sectional side elevation on line y-y, of Fig. 4.

Fig. 7 is a front elevation of a further form, two intermediate sections and the top and bottom sections being shown.

Fig. 7^a is a left end elevation of one of the sections (34) shown in Fig. 7, removed.

Fig. 7^b is a plan of the section shown in Fig. 7^a.

Fig. 8 is a front elevation illustrating another modification, and representing two intermediate sections.

Fig. 9 is a plan of Fig. 8.

Fig. 10 is a front elevation of another form, illustrating two intermediate sections, and

Fig. 11 is a plan of Fig. 10.

Referring more particularly to the construction represented in Figs. 1 to 3, the extensible or adjustable sectional post or pillar comprises a lowermost section 1, which will be rigidly fixed to the cover, (not shown) of the binder, ledger, et cetera, or to a member or bar 2, attached preferably to the lower or bottom cover (not shown) of the binder, et cetera,—by providing it at the bottom at opposite sides with projecting pieces 2^a, which pass through the bar 2 and are bent over,—and any requisite number of intermediate sections 3 and a top section or cap 4. The number of sections will depend on the aggregate thickness of leaves which are to be bound or held in the binder, ledger, et cetera. The bottom section 1 and all the intermediate sections 3, as shown, each consist of three parts, that is to say a casing,

body or hollow main part 5, a solid U-shaped part 6, fixed in one end of the hollow part 5 with the end parts 7, 8, projecting beyond the one end of said casing 5, and 5 a spring retaining piece 9, attached to the casing and projecting beyond the end of the casing and between the projecting parts 7, 8. The rivet or the like 10, which fixes the U-shaped part 6, may also be used as the 10 means for fixing the spring 9; and the latter, as shown, be placed in a recess in the side of the U-shaped part 6. The casing may be conveniently made from a piece of tubing and bent to the desired substantially 15 rectangular or oblong shape in cross section, with the edges rounded, as indicated at 11. Obviously the casing may be made from a piece of sheet metal bent to the required shape, in which event the rivet 10 may be used as the means for securing the casing at the joint.

The U-shaped part is positioned inside the casing so that a space or recess is provided in the casing extending from the inner 20 end of the U-shaped piece to the other end of the casing which is open-ended.

On the spring a pin or projection 12 is formed or fixed and in the casing a hole 13 is provided with which the pin or projection 30 12 on the spring of the adjoining section is caused to engage, when the sections are assembled. This engagement prevents disconnection of the sections until the pin or projection 12 is forced out of the hole 13, which 35 can be effected by any pointed instrument or article.

In assembling the sections, the open end of the casing 5 of the next upper section is projected or passed over the projecting parts 40 7, 8, of the U-shaped piece 6, together with the spring 9 lying between them, until the pin or projection 12 on the spring drops into engagement with the hole 13. The top section or cover 4, as shown, consists merely of a piece of tube 5^a flattened to substantially 45 rectangular shape and providing the space to receive the projecting parts 7, 8, and spring 9, and having the hole 13 for the pin or projection 12 on the spring to engage in. It may be closed at the top, if desired. Each of the posts or pillars may be built up by using the requisite number of the intermediate sections 3, then placing the cap or top section in position and then arranging 50 55 the top cover over the posts and fixing it in the manner usual with post binders. The retaining means for the top cover will engage with the upper ends of the sectional posts in the ordinary way.

60 Referring to the construction shown in Figs. 4 to 6, each section of the post consists of the casing or main part 14, which can also be conveniently constructed out of a piece of suitable metal tubing; a spring piece 15, which at one end is riveted to the main part

14, and projects for a suitable distance beyond one end thereof; and two pins or projections 16, which extend beyond the end of the main part 14, at the opposite end to the spring 15, and at the sides of said main part. 70 The two pins or projections 16, may be parts of a U-shaped piece 17, part of which is placed in the main part 14, so that the pins or ends 16 project for the desired distance beyond the end of the casing and are adapted to engage with the holes 16^a provided in the sides of the next adjoining section, to connect the sections. These pins or projections 16 may be retained in position by pressing the tube together so that the pins 16 are gripped at the sides of the casing 14; and the cross bar 18 of the U-shaped piece 17 is so positioned that when the tube is pressed together or flattened, a rib, ridge or projection 19 is formed between the raised vertical sides or edges 20, of the casing 14. This rib, ridge or projection 19 serves as the part which the end of the spring 15 of the adjoining section engages, to connect the sections of the post. The outer end of the spring 15 of each section is curved, bent or shaped, as indicated at 21, to engage and more or less fit the rib or projection 19. The rib or projection 19 may be made flat at the top, where the spring 15 engages with it, as indicated at 22, to ensure a better engagement. The engagement between the spring 15 and the rib 19 prevents the accidental disengagement of the sections of the post.

90 The top section or cap 24 comprises the casing 14^a and the U-shaped part 17 providing the projecting pins 16. As shown in Fig. 4, the holes 16^a in the casing 14^a may be closed at the top, as indicated at 25.

95 The rib 19 may be formed on the casing 14 in any other preferred manner or the spring 15 may be constructed to engage in a hole or recess, or with any other suitably shaped projection on the casing.

100 In the case of the bottom section, or that one which is fixed to the back or cover of the binder, ledger, et cetera, or a part thereof, the projecting pins 16, as shown in Fig. 4, may be utilized as the means for securing it in position on the back cover. The pins can pass through holes 23 in the back or cover or part thereof, and, as shown, be riveted thereto on the underside.

105 Referring to the construction shown in Fig. 7, each section of the post comprises the generally flat member 26 or 26^a, having a hole 27 extending down both vertical edges; which may as shown be made from a flat piece of metal plate bent round to form the holes 27.

110 The lowermost section may be constructed with projecting pieces 28 for securing it to the cover or a part thereof. The bottom section 29 is constructed in the one side at the top with a recess or groove 30, intersect-

ing the vertical hole 31 down the one edge, which recess or groove 30 leaves or provides a lug or projection 32 at or near the top of said side. The section 29 is also cut away at the top of the other side so that the top of the hole 33 provided down this edge is approximately on a level with the bottom of the recess or groove 30 in the opposite edge.

10 The adjoining section 34, which is adapted to engage with said lowermost section 29, is provided with a pin or projecting piece 35 at the bottom of the one side. This pin 35 will be tightly fitted into and secured 15 in the hole 36 formed down the edge of said side, and it is adapted to fit into the top of the hole 33 provided at the cut-away side of the bottom section. At the bottom of the other side of the adjoining section 34, 20 a recess or groove 37 is formed which leaves or provides a lug or projection 38, like the lug or projection 32 on the top of the bottom section 29, the bottom of the section 34 overlapping or extending below the top of 25 the adjoining section 29, beneath it. The pin 35 which fits into the hole 33 in the one side of the bottom section 29 serves as a hinge about which the adjoining section 34 can be turned to place the bottom lug or 30 projection 38 thereof in engagement with the recess or groove 30 in the top of one side of the bottom section 29. The adjoining section 34 at the top is constructed the same as the top of the bottom section 29, 35 but the section 34 is turned so that its right and left sides are in reversed relation. The lug 39 at the top of said adjoining section 34 is placed at the top of that side or edge in which the pivot or hinge pin 35 is provided, and diagonally opposite the bottom lug 38.

Consequent upon this construction the hinge pin of each succeeding section is located at opposite sides of the built-up post. 45 Any further intermediate sections 40 may be identical with section 34.

The cap 41, as shown, is constructed at the bottom with the hinge pin 42 on the one side and the lug 43 and recess 44 at the bottom on the other side and made flat at the top. The dotted lines indicate the cap turned about its hinge pin to disengage it from the adjoining section.

The lugs are held in the grooves by the 55 sheets, when placed on the posts, precluding the movement of the sections relative to each other.

Referring to that form of the invention shown in Figs. 8 and 9, each of the sections 60 is shown made of a tubular piece 45 pressed into substantially rectangular form. In one end of the tube 45 is arranged an intermediate piece 46, which extends at its one end inwardly to approximately the centre of the 65 length of the flattened tube, as indicated at

47, and projects therefrom at its other end, as indicated at 48. This projecting part 48 is of hook shape or formed with a recess 49 which is adapted to pass under and engage a pin or the like 50 fixed in the recess 70 formed by the flattened sides of the tube above the centre piece in the next adjoining section. The projecting part 48 is rounded off on the back to enable it to be inserted in the recess formed in the upper end of the casing or flattened tube 45 in assembling the sections. As in the previous construction the lowest section is fixed to the base member attached to one cover of the binder, and does not require the hook-shaped projection. 75

In the top edge of each section near one side a slight recess or groove 51 is formed which allows for the requisite radial movement of the section in putting it into position. 80

Referring now to the modification shown in Figs. 10 and 11, the connecting means between adjoining sections consists of flat pieces or plates 52, 53, slightly less than 90 half the width of the section, one of which, 52, projects from one end of the casing and the other 53, from the other end and at the opposite side. In this construction the friction between the projecting pieces or plates 52, 53, and the holes or recesses 54, 55, in the casing serves for keeping the parts together. The casing can conveniently consist, as in the previous construction, of a piece of flattened tubing, with the flat pieces or plates 52, 53, secured by pressing the sides of the tubular piece around the inner ends of said flat pieces or plates 52, 53, and riveting the same in position, as indicated 95 at 56. 100

The invention can be adopted in the construction of a non-extensible post by making such posts of substantially rectangular, oval, elliptical or other similar shape. 105

The means described for connecting together the sections of a built-up post can be adapted to the sections of an oval, round, square or other post of any preferred shape. 110

What I claim as my invention, and desire to protect by Letters Patent is:— 115

1. A rigid built-up post for loose leaf binders and the like, made up of separable sections each of which sections is of a greater dimension in one direction than in the other direction in transverse section, the sections being adapted to engage with each other, and means for retaining the sections in their engaging positions, as set forth. 120

2. A rigid built-up post for loose leaf binders and the like made up of separable sections each of which sections is of a greater dimension in one direction than the maximum dimension in the other direction in transverse section, including a bottom section having means for securing it to one 125 130

of the binder covers, an intermediate section, and a top section, all of said sections incorporating means for engaging each other, said latter means comprising recesses and projections on alternate sides of the sections and hinges on the other alternate sides of the sections, as set forth.

In testimony whereof I have signed my name to this specification in the presence of two subscribing witnesses.

ROBERT LYGERTWOOD ESSON.
